UNITED STATES PATENT OFFICE.

THOMAS NATHAN RUSSELL, OF CHICAGO, ILLINOIS, ASSIGNOR, BY MESNE ASSIGNMENTS, TO CHICAGO-CLEVELAND CAR ROOFING COMPANY, OF WILMINGTON, DELAWARE, A CORPORATION OF DELAWARE.

CAR ROOF.

Application filed June 4, 1918, Serial No. 238,085.

To all whom it may concern:

Be it known that I, THOMAS NATHAN RUSSELL, a citizen of the United States, residing in Chicago, in the county of Cook and State 6 of Illinois, have invented a new and useful Improvement in Car Roofs, of which the following is a specification.

My invention relates to car roofs of the "outside metal" type and has for an object 10 the providing of an outside metal roof construction that has extreme simplicity of application and ready replacement of parts without mutual interference and particularly insures freedom of movement in the 15 mutual engagement of the parts with each other and at the same time so retains the main roof-sheets on the substructure that their retaining means shall be securely applied well within the outer side-line of the 20 car in such a way as to guard against their disturbance or displacement by the side-wiping accidents that may occasion serious damage and loosening of a metal roof-covering; and the invention has for further 25 objects such other advantages and results as may be found to obtain in the structures hereinafter set forth and claimed.

In the accompanying drawings, forming 30 part of this specification, and showing for purposes of illustration a preferred embodiment of the subject-matter hereinafter claimed,

Fig. 1 is a top plan view of a car roof exemplifying my invention;

Fig. 2 is a section on the line 2—2 of Fig. 1;

Fig. 3 is an enlarged detail section of the ridge portion of the section shown in Fig. 2;

Fig. 4 is an enlarged detail section of the 40 eaves portion of the section shown in Fig. 2;

Fig. 5 is a perspective of a portion of one of the ridge-caps showing particularly the form of its portion that overlaps the transverse joints and caps of the roof;

Fig. 6 is a detail section on the line 6—6 of Fig. 1, showing particularly the application of the transverse joint cap and the hook strip and the flashing at the eaves;

Fig. 7 is a side elevation of the eaves 50 structure;

Fig. 8 is an enlarged top plan view showing the eaves end of the transverse joint and cap;

Fig. 9 is an enlarged section on the line

9—9 of Fig. 1 showing the relation of the 55 transverse joint caps to the sides of the roof sheets;

Fig. 10 is an enlarged top plan view of the ridge construction showing the application of the ridge caps at their overlapping 60 with each other and their intersection with the transverse joint and caps;

Fig. 11 is a section similar to Fig. 2 but showing a modified construction in which the roof is applied to a substructure that has 65 wooden beam side-plates instead of the metallic angle side-plates indicated in the previous figures;

Fig. 12 is a side elevation of the roof of 70 the same modified form to which Fig. 11 relates; and

Fig. 13 is an enlarged detail section of the eaves portion of the same modified form of roof to which Figs. 11 and 12 relate and shows the construction of such form at the 75 same place illustrated in Fig. 6.

Like reference numerals indicate like parts in all of the drawings.

20, 20 are the roof-sheets, each of which has an inverted U-shaped flange 21 along its ridge end, an under-bent hook flange 22 along its eaves-end and an upstanding inwardly-rebent flange 23 along each of its sides. These roof-sheets engage with each 80 other in pairs by the overlapping of their inverted U-shaped ridge flanges along the ridge line of the roof and occupy the spaces between the transverse mullions 24 that are nailed on the top of the wooden roof-sheathing 25 at intervals along the roof, the intervals between the successive mullions being 85 somewhat greater than the overall width of the said roof-sheets that occupy the spaces between these mullions, so that each roof-sheet has some free-space for movement laterally between the mullions on either side of it. Each mullion is capped with a mullion-cap 26, whose depending lateral flanges 90 considerably overhang the sides of the mullion and are inwardly rebent so that they 95 may be telescoped into and loosely engage with the aforesaid upstanding side-flanges 23 of the roof-sheets and still allow free movement of said roof-sheets toward and away from the mullions. The eaves-ends of 100 the mullions overhang the recess 27 that is rabbed out along the top of the eaves portion of the roof-sheathing; and the eaves-

105

end of each mullion-cap is bent downward and rebent inward to cover the eaves-ends of the engagement between the mullion-cap flanges and roof-sheet flanges and to hook 5 under and engage the said overhanging eaves-end of the mullion. The said rebent eaves-end flanges of the mullion-caps are indicated by the reference numeral 28. The mullion-caps are secured near the ridge by 10 the nails 29 that are driven through the mullions, mullion-caps and roof-sheathing and into the wooden ridge-pole sections 30 that span the space from carline to carline and are secured by the underneath ridge-plate 31 that extends under all of the car-lines. The overlapping ridge flanges of the roof-sheets and the ridge portions of the mullions and mullion-caps are capped along 15 the ridge-line by the ridge caps 32 that ship- 20 lap each other end for end and each of which has near one of its ends a portion shaped, as shown in Fig. 5, to fit over the intersection of the ridge portion of the mullion-caps and the seam formed by the over- 25lapping ridge-flanges of the roof-sheets. The running-board saddles 33 rest on top of the mullions and their caps, and each is se- 30cured by a bolt 34 passing down through the running-board saddle, ridge-cap, mullions, sheathing, ridge-pole and the underneath ridge-plate 31. It may be noted that the carlines are fewer in number than the mullion-divided spaces along the top of the roof and therefore do not directly underlie the 35 mullions, with the possible exception of the carline at the middle of the length of the roof. Each carline 35 is U-shaped and ex- 40 tends from side to side of the car, and in its channel there is a wooden filler 36; and so where the carline underlies the mullions at the middle of the length of the car the before-mentioned nails 29 would enter the 45 said wooden filler 36 of the carline and the said bolt 34 would pass through the said wooden filler and the bottom of the channel 50 of the carline and then through the underneath ridge-plate 31. Just underneath the top head of each bolt 34 there is a small water-proofing metal cap 37, let into a re- 55cess in the top of the running-board saddle, to prevent seepage of water into the bolt hole. The rebent eaves-flanges 22 of the roof-sheets are loosely engaged by the hook- 60 strips 39 that occupy the aforesaid recess along the eaves portion of the roof-sheath- 65ing and are secured well within the eaves- edge of said sheathing. These hook-strips extend along the entire length of the said eaves-recess and are made in sections that meet end for end. Overlying the under portion of these hook-strips and extending in between said portion and the rebent roof- 70sheet flange 22 that is engaged under the upper portion of the hook-strips, there is an eaves-flashing 40, the inner end of which is

flanged diagonally upward, at 41, and the outer portion of which is bent downward over the outside of the car and has its lower edge flaring outward somewhat to deflect drip water. In the form of structure shown 70 in Figs. 1 to 10, the said hook-strips 39 and flashings 40 are secured by the short bolts 42 positioned under each overhanging mul- 75 lion-end and extending down through the outwardly projecting upper member of the metallic angle side-plate 43. And in the form of structure shown in Figs. 11 to 13, the hook-strips are secured by the nails 44 driven through the hook-strip and roof- 80 sheathing and into the wooden side-plate, 85 and the flashings 40 are secured in their de- pending portion by the nails 46 driven through the side-sheathing 47 and into the wooden side-plate 45.

From the foregoing description, and from inspection of the drawings, it will be noted that the roof-sheets are so freely engaged along their sides and their eaves-ends that there is ample free-space for the shifting of their side flanges and eaves-flanges with- 90 in their engaging means, and that some free- 95dom of movement is allowed by the simple overlapping of the inverted U flanges along the ridge ends of said sheets, although the sheets are securely retained by such over- 100lapping ridge-flanges and by the ridge-caps that overlie them. It will further be noted that the retaining means along the eaves- 105ends of the roof-sheets, and such eaves-ends of the sheets themselves, are secured well 110 within the eaves-edge of the roof, and nothing overhangs said edge except the eaves- flashings that are independent of both the roof-sheets and their retaining hook-strips, so that a side-wiping accident that may 115 damage or rip away these eaves-flashings will neither damage nor detach either the roof-sheets or their retaining hook-strips. Other advantages will be apparent from the 120 description and drawings.

The invention as hereinabove set forth is embodied in a particular form of construction but may be variously embodied within the scope of the claim hereinafter made.

The invention may be embodied in forms of construction other than the specific form that has been shown and described for pur- 115poses of illustration, and still be within the scope and subject-matter of the claim here- 120inafter made.

I claim:

In a mullion roof for railway cars where- 125 in such mullions define roof spaces in which separate roof sheets are confined and in which all sides of each sheet are held in such manner that the sheet is free for move- 130ment longitudinally of the roof, the combi- nation of the mullion strips, roof sheets arranged between said mullion strips, mul- lion caps freely interlocked with the sides of

the roof sheets, the latter being freely movable with relation thereto, the eaves ends of said mullion caps being bent downwardly and thence inwardly under the eaves ends of the 5 mullion strips, the sheets and caps having reversely rebent flanges for such purpose which restrain vertical displacement of the sheets and caps, securing means for the ridge ends of the sheets which restrains them 10 from movement towards the eaves but leaves them free for the said longitudinal movement paralleling the ridge axis of the roof, and securing means within the eaves lines of the roof confining the eaves ends of the sheets from upward movement and leaving them free for said longitudinal movement.

In testimony whereof, I have hereunto set my hand.

THOMAS NATHAN RUSSELL.
